**WINDOW STRUCTURE AND SASH SLIDE RAILS
AND METHOD OF MAKING SUCH ASSEMBLY**

Benedict R. Gerulis, Grand Rapids, Mich., assignor to Grand Rapids Hardware Company, Grand Rapids, Mich.

Application May 21, 1956, Serial No. 586,254

6 Claims. (Cl. 20—12)

This invention relates to window structures of the frictional supported sash type and slide rail assemblies thereof and the method of producing such assemblies.

The main objects of this invention are:

First, to provide an improved window structure of the type in which the sash may be quickly inserted and removed and includes spring biased sash slide rails.

Second, to provide a unitary sash slide rail assembly including adjusting screws coacting with spring biased members mounted on a jamb, one which permits the quick mounting and detaching of the slide rail and the adjustment thereof to secure the desired biasing thrust on the slide rails to meet the requirements of the particular window assembly.

Third, to provide a method of making sash rail assemblies which results in economical production of uniform assemblies.

Objects relating to details and economies of the invention will appear from the description to follow. The invention is defined and pointed out in the claims.

A preferred embodiment of the invention is illustrated in the accompanying drawing, in which:

Fig. 1 is an enlarged fragmentary horizontal section of a window construction embodying my invention, the slide rail supporting and adjusting screw being shown in full lines.

Fig. 2 is a fragmentary front perspective view of the unitary sash slide rail of my invention.

Fig. 3 is an enlarged fragmentary view illustrating certain steps of my method.

Fig. 4 is a fragmentary view illustrating the final step of the method and apparatus for performing the same.

Fig. 5 is a plan view of a disc-like blank illustrating the first step in the method of producing the thrust element of the rail sash assembly embodying my invention.

Fig. 6 illustrates the second step in which the blank has been drawn or formed into a conical shape.

Fig. 7 is an enlarged sectional view showing the third step in the forming of the thrust element prior to the assembling step illustrated in Figs. 3 and 4.

In the accompanying drawing 1 represents the jamb or side rail of a window frame and 2 a stop thereof. 3 represents the vertical rail of a window sash having a longitudinal groove 4 therein. These parts are shown mainly conventionally except that the jamb is provided with an opening 5 adapted to receive means for springably biasing an element with which the screw 6 of the slide rail assembly coacts. The slide rail 7 is of inwardly facing channel section and is provided with a longitudinal rib 8 adapted to engage the longitudinal groove 4 in the sash rail 3.

The sash rail 7 is preferably provided with a plurality of supporting screws, as is illustrated in Fig. 2, but these are duplicates and therefore only one is illustrated and described in detail. The faces of the ribs of the sash rail have inwardly projecting or inwardly struck conical seats 9 therein adapted to rotatably support the peripherally conical heads 10 of the screws 6.

2

The screw 6 has an annular groove 11 at the base of its head in which the inturned flange 112 of the conical thrust member 113 is engaged. The screw is desirably rotatable relative to the conical thrust member which is conformed to embracingly fit the inner side of the screw head seat 9. The screw is thus effectively secured to the slide rail as an assembled unit and is adapted to sustain the thrust of a spring biased means mounted on the jamb to coact therewith.

10 The spring biasing means illustrated is that illustrated and described in the application of Claude J. Teggelaar, Serial No. 559,226, filed January 16, 1956, and which became Patent No. 2,774,996 on December 25, 1956. It should be understood, however, that my invention is not limited to use with such spring biasing means. The means illustrated comprises a base member 12 mounted in the opening 5 in the jamb 1 and provided with forwardly projecting arms 13 terminating in inturned stops 14. Coiled springs 15 are sleeved over these arms to project beyond the ends of the arms.

15 The coacting thrust member 16 is provided with inwardly projecting arms 17 disposed in telescoping relation to the arms 13 and provided with outturned hooks 18 which coact with the hooks 14 on the arms 13 to limit the outward movement of the thrust member under the action of the springs 15. The thrust member is provided with a spring abutment member 19 with which the screw 6 coacts. The screw 6 has threaded engagement with the member 19. Only one sash is illustrated in Fig. 1 a fragment of a slide rail for a second sash is shown.

20 The parts of the slide rail assembly may be quickly and rapidly assembled with uniform results. The thrust member and its engagement with the screw whereby the screw is rotatably mounted on the slide rail is an important feature of my invention. In Figs. 5, 6 and 7 I illustrate successive steps of forming the thrust member which serves the double purpose of receiving the thrust on the screw and also coacting with the head of the screw in retaining the parts of the slide rail assembly together.

25 Fig. 5 illustrates a circular disc-like blank 19 of sheet metal having a central hole 20 therein. The second step is to form the blank 19 into the cone shape shown in Fig. 6 which for identification is designated by the numeral 21. The third step is conforming the inner end of the part

30 21 to provide a flange 22 around the hole 20. In assembling, the screw is inserted through the opening in the seat 9 with its head 10 in supported engagement with the inner side of the wall thereof. The slide rail with the screw inserted therethrough is then positioned upon a bed member 24 having a raised conical portion 25 which fits into the outer end of the seat and in supporting engagement with the end of the screw as is shown in Fig. 4. The element 23 is then placed over the screw in supported engagement with the inner side of the conical seat of the rail. In this position the flange like portion 22 embraces the screw above the groove 11 therein, see Fig. 3.

35 The ram or upsetting member 26 has a conical recess 27 adapted to fittingly embrace the thrust element when the parts are in fully actuated position as shown in Fig. 4. The ram member has an annular shoulder 28 which, as shown in Fig. 3, engages the end of the flange portion 22 of the element. As the ram is actuated this flange portion 22 of the thrust member is turned inwardly and also portions above the flange are folded inwardly by the shoulder

40 28 until the inner end of the thrust member is turned to the position shown in Figs. 1 and 4 with the thrust member in retaining engagement with the groove. As the thrust is applied to the edges of the part 22 there is a tendency for the element 23 to bulge outwardly but that is limited by the wall 27, which when the ram 26 is fully actuated conforms and seats the thrust member against the inner side of the screw head seat.

The head of the screw and the part 25 of the bed member fit within the seat to support the wall of the seat so they cannot be distorted during this operation. This assembling operation may be very rapidly performed and on a simple press consisting of a bed member and ram, the bed member having means for properly locating and supporting the sash rail while the assembling operation is performed.

I have illustrated and described a very simple and practical apparatus for assembling the parts. As stated, the particular thrust assembly or spring biased thrust element is that illustrated in the said Teggelaar application, Serial No. 559,226 but these details form no part of my present invention. The improvement of my invention illustrated is highly practical.

I have not attempted to illustrate or describe certain modifications which I contemplate or which might be desirable for other types of window structures than that conventionally illustrated as it is believed that this disclosure will enable those skilled in the art to embody or adapt my invention as may be desired.

Having thus described the invention, what is claimed as new and is desired to be secured by Letters Patent is:

1. A window structure comprising a jamb, a springably biased thrust member mounted in said jamb, a sash having a vertically grooved side rail, a sash engaging slide rail having an outwardly projecting longitudinal rib engaging said groove in the sash, the rib having a conical screw head seat projecting inwardly from the face portion thereof and a screw opening at the center of the seat, a screw disposed through and rotatable in said opening and having threaded engagement with said thrust member, said screw having a conical head rotatably engaging said seat and an annular groove at the base of its head, and an outwardly facing conical thrust member having a central opening through which said screw is disposed thrustingly embracing the inner side of said conical seat and having an inturned flange-like portion at its inner end retainingly engaged in said groove in said screw, said screw being rotatable in said thrust member.

2. A window structure comprising a jamb, a springably biased thrust member mounted in said jamb, a sash engaging slide rail having a conical screw head seat struck inwardly therefrom, there being a screw opening at the center of the seat, a screw disposed through and rotatable in said opening and having threaded engagement with said thrust member, said screw having a conical head rotatably engaging said seat and an annular groove at the base of its head, and an outwardly facing conical thrust member disposed on the inner side of and thrustingly embracing said conical seat and having an inturned inner end portion retainingly engaged in said groove in said screw.

3. A window structure comprising a jamb, a springably biased thrust member mounted in said jamb, a sash engaging slide rail having a screw head seat struck inwardly therefrom, there being a screw opening at the center of the seat, a screw disposed through and rotatable in said opening and having threaded engagement with said thrust member, said screw having a head rotatably engaging said seat and an annular groove in its shaft, and an outwardly facing thrust member disposed on the inner side of and in thrusting relation to said seat and having an inner end portion retainingly engaged in said groove in said screw.

4. A slide rail assembly for window sash having a vertically grooved side rail comprising a slide rail having an outwardly projecting longitudinal sash groove engaging rib, the rib having a conical screw head seat struck inwardly from the face portion thereof, there being a screw opening at the center of the seat, a screw disposed through and rotatable in said opening for threaded engagement with a spring biased thrust member, said screw having a conical head rotatably engaging said seat and an annular groove at the base of its head, and an outwardly facing conical thrust member disposed at the inner side of and embracing the inner side of said conical seat and having an inturned flange-like portion at its inner end retainingly engaged in said groove.

5. A slide rail assembly for window sash comprising a slide rail having a conical screw head seat struck inwardly therefrom, there being a screw receiving opening at the center of the seat, a screw disposed through and rotatable in said opening for threaded engagement with a coacting thrust member, said screw having a conical head rotatably engaging said seat and an annular groove at the base of its head, and an outwardly facing conical thrust member disposed at the inner side of and embracing the inner side of said conical seat and having an inturned portion at its inner end retainingly engaged in said groove.

6. A slide rail assembly for window sash comprising a slide rail having a screw head seat struck inwardly from the face portion thereof, there being a screw opening at the center of the seat, a screw disposed through and rotatable in said opening for threaded engagement with a spring biased thrust member, said screw having a head rotatably engaging said seat and an annular groove in its shaft, and an outwardly facing thrust member disposed at the inner side of and in thrusting engagement with the inner side of said seat and having an inturned portion at its inner end retainingly engaged in said groove in said screw.
